UNITED STATES PATENT OFFICE.

WILLIAM E. FOWLER, JR., OF PITTSBURGH, PENNSYLVANIA, ASSIGNOR TO LIBERTY STEEL PRODUCTS COMPANY, INC., A CORPORATION OF NEW YORK.

BRAKE-BEAM FULCRUM.

1,389,041.

Specification of Letters Patent. Patented Aug. 30, 1921.

Application filed July 23, 1919. Serial No. 312,815.

To all whom it may concern:

Be it known that I, WILLIAM E. FOWLER, Jr., a citizen of the United States, and a resident of Pittsburgh, in the county of Allegheny and State of Pennsylvania, have made a new and useful Invention in Brake-Beam Fulcrums, of which the following is a specification.

My invention relates to trussed brake beams for railway rolling stock and consists of a fulcrum strut for such beams which is efficient, economical in manufacturing costs and easily applied to the other members of the beam.

It is customary to form such struts of bars which are bent and twisted to accommodate the members of the beam, the levers which operate the beam and which are connected thereto at an angle, and the fulcrum pins. This bending and twisting displaces the fibers of the bar so that they are no longer parallel with the strut axis and therefore do not offer the maximum resistance to compression stresses. Surplus metal is required to insure sufficient strength after distortion and to compensate for the results of stretching and upsetting the bar. One of the objects of my invention is to eliminate these undesirable features. Another object is to secure the well known strength of a cylindrical column which permits the most economical disposition of material for a given weight.

Briefly, I adopt rolled steel tubing as the chief element of my fulcrum strut and utilize it in the manner set forth below and illustrated in the accompanying drawings in which Figure 1 is mainly a plan, but in part a section, of my strut showing parts of the compression and tension members of the brake beam to which the strut is applied; Fig. 2 is a side view and section on line 2--2 of Fig. 1 and Fig. 3 is a section on line 3--3 of Fig. 2.

The body 1 of the strut consists of a section of steel tubing one end of which is closed by a casting 2 which forms a saddle for the beam tension member 3. The body of saddle 2 is of the same diameter as the tubing and is traversed by a groove 4 adapted to seat the tension member 3. A circular projection 5 extends within tubing 1 securing the saddle against transverse displacement. Projection 5 is undercut to

ward its shouldered union with the saddle body which allows the end of tube 1 to be swaged down over the projection to prevent longitudinal disassembly of the tube and saddle. To resist any tendencies toward relative rotation of tube 1 and saddle 2 I provide tube 1 with a slot 1^a and saddle 2 with a lug 5^a to fit therein and positively locate the two members with respect to each other.

At the opposite end of tube 1, the metal is split and one half of the split portion is bent to form a channel recess 6 for the reception of the flange of a compression member of the beam, shown herein as a T bar 7. I prefer to cut away the other half of the split portion at 8. A clip 9 having a channel recess 10 corresponding to recess 6 is provided for completely securing bar 7 in place. Clip 9 is assembled with the tube strut by a rivet 11 which grips the clip and tube and a spacing bushing 12. The portion which I cut away could, instead, be bent around member 7 similarly to portion 6 but the riveting of a separate clip is an easier operation.

Intermediate the ends of tube 1, I punch slots 13 on opposite sides of the tube for the accommodation of the brake lever and at right angles to the slots I provide holes 14 for the lever pin. In punching holes 14 instead of shearing the metal included in the circumference of the hole from the surrounding metal, I press it into the boss shape 15 thereby extending the wall of the hole which forms the pin bearing surface. This enlargement of the bearing surface gives the area for the pin bearing required by the Master Car Builders' standards without the addition of any extra parts such as are frequently used and a type of which are shown in United States Letters Patent 1,146,860 issued to me July 20, 1915.

The strut described herein is very cheap in material cost and requires slight labor expenditure to manufacture or apply to the other members of the beam. The strut only requires a length of standard tubing, a small and simple casting, a small forging, a bushing and a rivet. From compression member to tension member the fibers of the tube run parallel to the strut axis and to the line of stress produced by the other beam members under initial compression and under

service loads. The lever slots are formed by shearing of the metal, not by twisting it and the disposition of the material forming the fulcrum pin holes permits the use of 5 comparatively thin walls without departing from the required area for the pin. The strut is adequately locked against rotation relative to the other beam members. If other shapes are used for the compression 10 member in place of the T bar illustrated, no material change in the form of the strut will be necessitated.

I claim:—

1. A strut for a trussed brake beam, 15 formed substantially of wrought metal tubing and provided with a lever fulcrum between its ends.

2. A strut for a trussed brake beam, 20 comprising a section of wrought metal tubing provided with means at its opposite ends for securing the compression and tension members of the beam and adapted to fulcrum a brake lever between its ends.

3. A fulcrum strut for a trussed brake 25 beam, comprising a length of wrought metal tubing which is provided with slotted passages for the beam lever and bearings for the lever fulcrum pin.

4. A fulcrum strut for a trussed brake 30 beam, formed substantially of a wrought metal tube which has sections of its wall removed for the passage of the beam lever and sections of its wall displaced to form fulcrum pin bearing surfaces of greater 35 length than the thickness of the tube wall.

5. A fulcrum strut for a trussed brake 40 beam, comprising a wrought metal tube fitted at one end with a grooved saddle adapted to receive a beam tension member and at the opposite end with grooved shoulder adapted to receive a flanged compression member.

6. A fulcrum strut for a trussed brake 45 beam, comprising a section of metal tubing split at one end with the split portion shaped to form bearing and retaining surfaces for a compression member of the beam.

7. A fulcrum strut for a trussed brake 50 beam, comprising a metal tube one end of which is fitted with a tension member saddle having an undercut projection within said

tube, said tube being reduced about said undercut projection.

8. A fulcrum strut for a trussed brake beam, comprising a metal tube one end of 55 which is fitted with a metal saddle for a beam tension member, said end having a longitudinal slot and said saddle having a lug adapted to enter said slot when said tube and saddle are assembled.

9. A fulcrum strut for a trussed brake beam, comprising a rolled metal tube provided with an integral extension at one end 65 bent to form a seat and grip for one side of a beam member and a cooperating clip for the other side of said member secured to said tube.

10. A fulcrum strut for a trussed brake beam, comprising a length of rolled metal tubing having diametrically opposite portions of its wall removed to form brake lever slots and having diametrically opposite portions of its wall expressed to form cylindrical pin bearings of greater area than that which would be provided by punching through the 75 normal thickness of the tube wall.

11. A tubular strut for a trussed brake beam, adapted to receive a lever between its ends and formed substantially of fibrous metal with the fibers parallel to the strut 80 axis substantially throughout the strut.

12. A strut of fibrous metal adapted to space the compression and tension members of a brake beam, to provide for the fulcruming of a brake lever between its ends, and having the major portion of its fibers extending substantially from the beam compression member to the beam tension member without distortion.

13. A strut for a trussed brake beam, 90 consisting of a fibrous metal tube having, between its ends, integral bearings for a lever fulcrum pin and slots which form a passage for a brake lever and having its fibers extending parallel with the tube axis substantially from end to end except at said slots and bearings.

In testimony whereof, I have hereunto subscribed my hand this 15th day of July, 1919.

WILLIAM E. FOWLER, JR.
